(57) **ABSTRACT**

A refrigeration system includes pressure-regulating valve positioned between two flash tanks and a heat exchanger is positioned downstream from a medium temperature compressor. After determining that operation of an evaporator in a defrost mode is indicated, the system causes the evaporator to operate in the defrost mode by adjusting the pressure-regulating valve to increase a pressure of a first flash tank relative to a pressure of a second flash tank, allowing flow of refrigerant from the first flash tank to the heat exchanger, and allowing refrigerant heated by the heat exchanger to flow to the first evaporator.

FIG. 1

FIG. 2

FIG. 3

HOT GAS DEFROST USING FLUID FROM HIGH PRESSURE TANK

TECHNICAL FIELD

This disclosure relates generally to refrigeration systems. More particularly, in certain embodiments, this disclosure relates to hot gas defrost using fluid from a high pressure tank.

BACKGROUND

Refrigeration systems are used to regulate environmental conditions within an enclosed space. Refrigeration systems are used for a variety of applications, such as in supermarkets and warehouses, to cool stored items. For example, refrigeration systems may provide cooling operations for refrigerators and freezers.

SUMMARY OF THE DISCLOSURE

During operation of refrigeration systems, ice may build up on evaporators. These evaporators need to be defrosted to remove ice buildup and prevent loss of performance. Previous evaporator defrost processes are limited in terms of their efficiency and effectiveness. For example, using previous technology, defrost processes may take a relatively long time and consume a relatively large amount of energy. In some cases, previous technology may be incapable of providing adequate defrosting, for instance, in cases where a relatively large number of evaporators need to be defrosted in a multiple-evaporator refrigeration system.

This disclosure provides technical solutions to the problems of previous technology, including those described above. For example, a refrigeration system is described that facilitates improved evaporator defrost using refrigerant from a flash tank maintained at an increased pressure during defrost operation. While one or a portion of the evaporators of the refrigeration system are operating in a normal refrigeration mode, other evaporator(s) can be operated in a defrost mode using refrigerant heated by the hot gas produced by the refrigeration process. An auxiliary flash tank receives refrigerant from a gas cooler. A heat exchanger is positioned downstream from medium-temperature (MT) compressor(s) and transfers heat from compressed refrigerant output by the MT compressor(s) to a flow of refrigerant from the auxiliary flash tank. Embodiments of this disclosure may provide improved defrost operations to evaporators of refrigeration systems, such as CO₂ refrigeration systems. In certain embodiments, the refrigeration system does not require specialized high pressure evaporator components because hot gas is provided at a moderate pressure from the auxiliary flash tank. Accordingly, system complexity and cost may be decreased. The refrigeration system may also facilitate flexible operation via use of the auxiliary flash tank, which can be operated, for example, at a selected pressure to adjust defrost performance. Certain embodiments may include none, some, or all of the above technical advantages. One or more other technical advantages may be readily apparent to one skilled in the art from the figures, descriptions, and claims included herein.

In an embodiment, a refrigeration system includes a plurality of evaporators, one or more medium temperature compressors configured to output compressed refrigerant, a first flash tank configured to receive and store cooled refrigerant provided by a gas cooler, a second flash tank configured to receive and store a portion of the cooled refrigerant

from the first flash tank, a pressure-regulating valve disposed in refrigerant conduit coupling the first flash tank to the second flash tank, a heat exchanger, and a controller. Each evaporator is configured to transfer heat from a space to refrigerant. The heat exchanger is positioned downstream from the one or more medium temperature compressors and configured, when at least one evaporator of the plurality of evaporators is operated in a defrost mode, to transfer heat from the compressed refrigerant output by the one or more medium temperature compressors to a flow of refrigerant from the first flash tank. The controller is communicatively coupled to the pressure-regulating valve. The controller is configured to determine that operation of a first evaporator of the plurality of evaporators in a defrost mode is indicated. After determining that operation of the first evaporator in the defrost mode is indicated, the controller causes the first evaporator to operate in the defrost mode by adjusting the pressure-regulating valve to increase a pressure of the first flash tank relative to a pressure of the second flash tank, allowing flow of refrigerant from the first flash tank to the heat exchanger, and allowing refrigerant heated by the heat exchanger to flow to the first evaporator.

BRIEF DESCRIPTION OF THE DRAWINGS

For a more complete understanding of the present disclosure, reference is now made to the following description, taken in conjunction with the accompanying drawings, in which:

FIG. 1 is a diagram of an example refrigeration system of this disclosure configured to operate evaporators in a refrigeration mode;

FIG. 2 is a diagram of the example refrigeration system of FIG. 1 configured to operate an evaporator in a defrost mode; and

FIG. 3 is a flowchart of an example method of operating the refrigeration system of FIGS. 1 and 2 to provide improved evaporator defrost.

DETAILED DESCRIPTION

Embodiments of the present disclosure and its advantages are best understood by referring to FIGS. 1-3 of the drawings, like numerals being used for like and corresponding parts of the various drawings.

As described above, prior to this disclosure, defrost operations of refrigeration systems suffered from certain inefficiencies and drawbacks. The refrigeration system of this disclosure provides improvements in defrost performance and energy efficiency. The refrigeration system of this disclosure may be a CO₂ refrigeration system. CO₂ refrigeration systems may differ from conventional refrigeration systems in that these systems circulate refrigerant that may become a supercritical fluid (i.e., where distinct liquid and gas phases are not present) above the critical point. As an example, the critical point for carbon dioxide (CO₂) is 31° C. and 73.8 MPa, and above this point, CO₂ becomes a homogenous mixture of vapor and liquid that is called a supercritical fluid. This unique characteristic of transcritical refrigerants is associated with certain operational differences between transcritical and conventional refrigeration systems. For example, transcritical refrigerants are typically associated with discharge temperatures that are higher than their critical temperatures and discharge pressures that are higher than their critical pressures. When a transcritical refrigerant is at or above its critical temperature and/or pressure, the refrigerant may become a “supercritical

fluid”—a homogenous mixture of gas and liquid. Supercritical fluid does not undergo phase change process (vapor to liquid) in a gas cooler as occurs in a condenser of a conventional refrigeration system circulating traditional refrigerant. Rather, supercritical fluid cools down to a lower temperature in the gas cooler. Stated differently, the gas cooler in a CO₂ transcritical refrigeration system may receive and cool supercritical fluid, and the transcritical refrigerant undergoes a partial state change from gas to liquid as it is discharged from an expansion valve.

Refrigeration System

FIGS. 1 and 2 illustrate an example refrigeration system 100 configured for improved defrost operation. The refrigeration system 100 shown in FIG. 1 is configured to operate evaporators 116, 128 in a refrigeration mode, such that the evaporators 116, 128 provide cooling to a corresponding space, such as a freezer and deep freeze, respectively (not shown for clarity and conciseness). FIG. 2 illustrates the example refrigeration system 100 when configured for operation of evaporator 128 in a defrost mode, such that evaporator 128 is defrosted and evaporator 116 still provides cooling to a space. When at least one of the evaporators 116, 128 is operated in the defrost mode, refrigerant from an auxiliary flash tank 130 is provided to a heat exchanger 106 downstream from MT compressor(s) 102. This refrigerant is heated via heat transfer with heated, compressed refrigerant output by the MT compressor(s) 102 and provided for defrost of the evaporator(s) 116, 128 being operated in the defrost mode. The refrigerant removes ice buildup from coils of the evaporator(s) 116, 128.

Refrigeration system 100 includes one or more medium-temperature (MT) compressors 102, refrigerant conduit subsystem 104, heat exchanger 106, pressure-regulating valve 118, gas cooler 108, primary flash tank 112, auxiliary flash tank 130, one or more MT evaporators 116 and corresponding valves 114, 120, 122, 124, one or more low-temperature (LT) evaporators 128 and corresponding valves 126, 132, 134, 136, one or more LT compressors 138, a valve 140, a flash-gas bypass valve 142, and controller 150. In some embodiments, refrigeration system 100 is a transcritical refrigeration system that circulates a transcritical refrigerant such as CO₂.

The MT compressor(s) 102 are configured to compress refrigerant discharged from the MT evaporator(s) 116 that are operating in refrigeration mode (as shown in FIGS. 1 and 2) and provide supplemental compression to refrigerant discharged from any of the LT evaporators 128 that are operating in refrigeration mode (as shown in FIG. 1). Refrigeration system 100 may include any suitable number of MT compressors 102. MT compressor(s) 102 may vary by design and/or by capacity. For example, some compressor designs may be more energy efficient than other compressor designs, and some MT compressors 102 may have modular capacity (e.g., a capability to vary capacity). The controller 150 is in communication with the MT compressors 102 and controls their operation.

Refrigerant conduit subsystem 104 facilitates the movement of refrigerant (e.g., CO₂) through a refrigeration cycle, such that the refrigerant flows in the refrigeration mode as illustrated by the arrows in FIG. 1. The refrigerant conduit subsystem 104 includes conduit, tubing, and the like that facilitate the movement of refrigerant between components of the refrigeration system 100.

Heat exchanger 106 is located downstream of the gas cooler 108 and configured to receive cooled refrigerant from the gas cooler 108. The heat exchanger 106 may include one or more tubes and/or coils that facilitate heat transfer

between refrigerant received from the MT compressor(s) 102 and refrigerant received (if any) from the auxiliary flash tank 130. When at least one of the evaporators 116, 128 is operating in defrost mode, as shown in FIG. 2, refrigerant from the auxiliary flash tank 130 flows to the heat exchanger 106. For instance, in the example of FIG. 2 in which the LT evaporator 128 is operating in defrost mode, valve 134 is open to allow refrigerant flow from the auxiliary flash tank 130 to the heat exchanger 106. Heat transfer occurs between the refrigerant from the auxiliary flash tank 130 and the compressed refrigerant from MT compressor(s) 102. This heat transfer results in heating of the refrigerant from the auxiliary flash tank 130. The heated refrigerant is provided to the evaporator(s) 116, 128 operating in the defrost mode. FIG. 2 shows this flow of refrigerant for the example scenario of the LT evaporator 128 operating in the defrost mode.

In addition to providing heated refrigerant for defrosting evaporators 116, 128, heat exchanger 106 may provide pre-cooling to refrigerant circulating through the refrigeration system 100. When none of the evaporators 116, 128 are operating in defrost mode, as shown in FIG. 1, generally little or no heat transfer takes place in the heat exchanger 106 because there is no refrigerant flowing from the auxiliary flash tank 130 (e.g., because valves 122 and 134 are closed). Heat exchanger 106 discharges refrigerant, whether not pre-cooled as in FIG. 1 or pre-cooled as in FIG. 2, to the gas cooler 108.

Gas cooler 108 is generally operable to receive refrigerant (e.g., from heat exchanger 106) and apply a cooling stage to the received refrigerant. In some embodiments, gas cooler 108 is a heat exchanger comprising cooler tubes configured to circulate the received refrigerant and coils through which ambient air is forced. Inside gas cooler 108, the coils may absorb heat from the refrigerant, thereby cooling the refrigerant.

Auxiliary flash tank 130 is configured to receive mixed-state refrigerant and separate the received refrigerant into flash gas and liquid refrigerant. Auxiliary flash tank 130 may include one or more tanks operable to hold refrigerant at least temporarily. Typically, the flash gas collects near the top of auxiliary flash tank 130, and the liquid refrigerant is collected in the bottom of auxiliary flash tank 130. A valve 110 may be disposed at or near an inlet of the auxiliary flash tank 130 to reduce pressure of refrigerant received by the auxiliary flash tank 130. The auxiliary flash tank 130 is coupled to the primary flash tank 112 via refrigerant conduit of the refrigerant conduit subsystem 104. As with the auxiliary flash tank 130, flash gas collects near the top of primary flash tank 112, and liquid refrigerant is collected in the bottom of primary flash tank 112.

A pressure-regulating valve 118 is disposed in the conduit coupling the auxiliary flash tank 130 to the primary flash tank 112. When both evaporators 116 and 128 are operated in refrigeration mode (see FIG. 1), the auxiliary flash tank 130 and primary flash tank 112 are held at about the same pressure with valve 118 fully open. Under these conditions, the two flash tanks 112 and 130 function similarly to a single larger tank. The liquid refrigerant from primary flash tank 112 flows to and provides cooling to the MT evaporator 116 and LT evaporator 128 (see FIG. 1). When evaporator 128 is operated in defrost mode (see FIG. 2), valve 118 is adjusted (e.g., at least partially closed) to increase the pressure in the auxiliary flash tank 130 relative to the primary flash tank 112 (e.g., by 50 psi). Hot gas refrigerant provided to defrost evaporator 128 is provided to primary flash tank 112. Flash gas from the primary flash tank 112 is

provided to the MT compressor(s) 102. Valve 140 may be a pressure regulating valve that adjusts the pressure of refrigerant provided to the flash tank 112 as appropriate to facilitate refrigerant flow as illustrated in FIG. 2

When operated in refrigeration mode (see FIG. 1), the MT evaporator 116 receives cooled liquid refrigerant from the primary flash tank 112 and uses the cooled refrigerant to provide cooling. As an example, the evaporator 116 may be part of a refrigerated case and/or cooler for storing items that must be kept at particular temperatures. The refrigeration system 100 may include any appropriate number of MT evaporators 116 with the same or a similar configuration to that shown for the example MT evaporator 116 shown in FIGS. 1 and 2.

Each of the one or more MT evaporators 116 has corresponding valves 114, 120, 122, 124 to facilitate operation of the MT evaporator 116 in a refrigeration mode and a defrost mode. Valve 114 may be an expansion valve. Expansion valve 114 may be configured to receive liquid refrigerant from primary flash tank 112 and reduce the pressure of the received refrigerant. In some embodiments, this reduction in pressure causes some of the refrigerant to vaporize. Valves 120, 122, 124 may be any appropriate motorized or electronically controllable valves, such as motorized ball valves, solenoid valves, and/or the like. The controller 150 is in communication with valves 114, 120, 122, 124 and controls their operation.

When the MT evaporator 116 is operated in the refrigeration mode illustrated in FIGS. 1 and 2, the first valve 114 upstream of the evaporator 116 is open and the second valve 120 downstream of the evaporator 116 is open. The third valve 124 and fourth valve 122 are both closed. In this configuration, the liquid refrigerant from primary flash tank 112 flows through expansion valve 114, where the pressure of the refrigerant is decreased, before it reaches the evaporator 116. Expansion valve 114 may be configured to achieve a refrigerant temperature into the evaporator 116 at a pre-defined temperature for a given application (e.g., about -6° C.). Refrigerant from the MT evaporator 116 that is operating in refrigeration mode is provided to the one or more MT compressors 102.

When the MT evaporator 116 is operated in the defrost mode (not shown for conciseness), valve 122 is at least partially opened to allow flow of refrigerant from the auxiliary flash tank 130 to the heat exchanger 106. Valve 118 may be adjusted to increase the pressure of the auxiliary flash tank 130 relative to the pressure of the primary flash tank 112 and help drive the flow of refrigerant to the heat exchanger 106. The first valve 114 upstream of the evaporator 116 is closed, and the second valve 120 downstream of the evaporator 116 is closed. Third valve 124 is opened to allow flow of compressed refrigerant from the heat exchanger 106 toward the MT evaporator 116 and back to the flash tank 112 after the refrigerant aids in defrosting the evaporator 116. In this configuration, refrigerant from auxiliary flash tank 130 is heated by the heat exchanger 106, flows through the evaporator 116, and defrosts the evaporator 116. Refrigerant exiting the evaporator 116 flows through the opened valve 124 and to the primary flash tank 112, which is at a lower pressure than the auxiliary flash tank 130.

Once defrost mode operation is complete, the controller 150 may end defrost mode operation and return to refrigeration mode operation by opening valve 118, closing valves 122 and 124, and opening valves 114 and 120. In some embodiments, the controller 150 may cause defrost mode to end after a predefined period of time included in the instruc-

tions 158 and/or schedule 162. In some embodiments, the controller 150 may cause defrost mode operation to end after predefined conditions indicated in the instructions 158 are reached (e.g., after a temperature and/or pressure 160 measured by sensor 144 reaches a threshold 164).

The LT evaporator 128 is generally similar to the MT evaporator 116 but is configured to operate at lower temperatures (e.g., for deep freezing applications near about -30° C. or the like). When operated in refrigeration mode (see FIG. 1), the LT evaporator 128 receives cooled liquid refrigerant from the primary flash tank 112 and uses the cooled refrigerant to provide cooling. As an example, the evaporator 128 may be part of a deep freezer for relatively long-term storage of perishable items that must be kept at particular temperatures. For clarity and conciseness, the components of a single LT evaporator 128 are illustrated. The refrigeration system 100 may include any appropriate number of LT evaporators 128 with corresponding valves 126, 132, 134, 136.

The LT evaporator 128 includes valves 126, 132, 134, 136 to facilitate operation of the LT evaporator 128 in a refrigeration mode (see FIG. 1) and a defrost mode (see FIG. 2). Valve 126 may be an expansion valve that is the same as or similar to valve 114, described above. Expansion valve 126 may be configured to receive liquid refrigerant from primary flash tank 112 and reduce the pressure of the received refrigerant. In some embodiments, this reduction in pressure causes some of the refrigerant to vaporize. Valves 132, 134, 136 may be any appropriate motorized or electronically controllable valves, such as motorized ball valves, solenoid valves, and/or the like (e.g., the same as or similar to valve 120, 122, 124, described above). The controller 150 is in communication with valves 126, 132, 134, 136 and controls their operation.

When the LT evaporator 128 is operated in the refrigeration mode illustrated in FIG. 1, the first valve 126 upstream of the evaporator 128 is open and the second valve 132 downstream of the evaporator 128 is open. The third valve 134 and fourth valve 136 are both closed. In this configuration, the liquid refrigerant from primary flash tank 112 flows through expansion valve 126, where the pressure of the refrigerant is decreased, before it reaches the evaporator 128. Expansion valve 126 may be configured to achieve a refrigerant temperature into the evaporator 128 at a pre-defined temperature for a given application (e.g., about -30° C.). Refrigerant from the LT evaporator 128 that is operating in refrigeration mode is provided to the one or more LT compressors 138.

When the LT evaporator 128 is operated in the defrost mode of FIG. 2, valve 134 is at least partially opened to allow flow of refrigerant from the auxiliary flash tank 130 to the heat exchanger 106. Valve 118 may be adjusted to increase the pressure of the auxiliary flash tank 130 relative to the pressure of the primary flash tank 112 and help drive the flow of refrigerant to the heat exchanger 106. The first valve 126 upstream of the evaporator 128 is closed, and the second valve 132 downstream of the evaporator 128 is closed. Third valve 136 is opened to allow flow of compressed refrigerant from the heat exchanger 106 toward the LT evaporator 128 and back to the flash tank 112 after the refrigerant aids in defrosting the evaporator 128. In this configuration, refrigerant from auxiliary flash tank 130 is heated by the heat exchanger 106, flows through the evaporator 128, and defrosts the evaporator 128. Refrigerant exiting the evaporator 128 flows through the opened valve 136 and to primary flash tank 112.

Once defrost mode operation is complete, the controller 150 may end defrost mode operation and return to refrigeration mode operation by opening valve 118, closing valves 134 and 136, and opening valves 126 and 132, as shown in the example of FIG. 1. In some embodiments, the controller 150 may cause defrost mode to end after a predefined period of time included in the instructions 158 and/or schedule 162. In some embodiments, the controller 150 may cause defrost mode operation to end after predefined conditions indicated in the instructions 158 are reached (e.g., after a temperature and/or pressure 160 measured by sensor 146 reaches a threshold 164).

The temperature and/or pressure sensors 144, 146 may be disposed on, in, or near the corresponding evaporators 116, 128 or refrigerant conduit connected to the evaporators 116, 128. Information from sensors 144, 146 may assist in determining when operation in defrost mode is appropriate or should be ended. For example, if the temperature and/or pressure 160 measured by sensors 144, 146 indicates potential freezing of the MT evaporator 116 and/or LT evaporator 128, defrost mode operation may be indicated. In some cases, defrost mode operation is determined to be indicated based on a schedule 162 (e.g., defrost mode operation may be performed at certain predefined time intervals or at certain times).

Valves 114, 120, 122, and 124 for the MT evaporator 116 and valves 126, 132, 134, and 136 for the LT evaporator 128 may be in communication with controller 150, and the controller 150 may provide instructions for adjusting these valves 114, 120, 122, 124, 126, 132, 134, 136 to open or closed positions to achieve the configurations described above for refrigeration mode operation and defrost mode operation. For example, instructions 158 implemented by the processor 152 of the controller 150 may determine that operation of the MT evaporator 116 and/or the LT evaporator 128 in a defrost mode is indicated. For example, instructions 158 stored by the controller 150 may indicate that defrost mode operation is needed on a certain schedule 162 or at a certain time. As another example, a temperature and/or pressure 160 of the evaporators 116, 128 may indicate that defrost mode operation is needed (e.g., because the temperature and/or pressure 160 indicates that expected cooling performance or efficiency is not being obtained).

Flash gas bypass valve 142 may be located in refrigerant conduit of the conduit subsystem 104 connecting the primary flash tank 112 to the MT compressor(s) 102 and configured to open and close to permit or restrict the flow of flash gas discharged from primary flash tank 112. In some embodiments, controller 150 controls the opening and closing of flash gas bypass valve 142. As depicted in FIGS. 1 and 2, closing flash gas bypass valve 142 may restrict flash gas from flowing to MT compressor(s) 102, and opening flash gas bypass valve 142 may permit flow of flash gas to MT compressor(s) 102.

As described above, controller 150 is in communication with at least valve 118; valves 114, 120, 122, and 124 of the MT evaporator 116; valves 126, 132, 134, and 136 of the LT evaporator 128; and compressors 102, 138. The controller 150 adjusts operation of components of the refrigeration system 100 to operate the evaporators 116, 128 in refrigeration mode or defrost mode, as described herein. The controller 150 includes a processor 152, memory 154, and input/output (I/O) interface 156. The processor 152 includes one or more processors operably coupled to the memory 154. The processor 152 is any electronic circuitry including, but not limited to, state machines, one or more central processing unit (CPU) chips, logic units, cores (e.g., a

multi-core processor), field-programmable gate array (FPGAs), application specific integrated circuits (ASICs), or digital signal processors (DSPs) that communicatively couples to memory 154 and controls the operation of refrigeration system 100.

The processor 152 may be a programmable logic device, a microcontroller, a microprocessor, or any suitable combination of the preceding. The processor 152 is communicatively coupled to and in signal communication with the memory 154. The one or more processors are configured to process data and may be implemented in hardware or software. For example, the processor 152 may be 8-bit, 16-bit, 32-bit, 64-bit or of any other suitable architecture. The processor 152 may include an arithmetic logic unit (ALU) for performing arithmetic and logic operations, processor registers that supply operands to the ALU and store the results of ALU operations, and a control unit that fetches instructions from memory 154 and executes them by directing the coordinated operations of the ALU, registers, and other components. The processor 152 may include other hardware and software that operates to process information, control the refrigeration system 100, and perform any of the functions described herein (e.g., with respect to FIGS. 1-3). The processor 152 is not limited to a single processing device and may encompass multiple processing devices. Similarly, the controller 150 is not limited to a single controller but may encompass multiple controllers.

The memory 154 includes one or more disks, tape drives, or solid-state drives, and may be used as an over-flow data storage device, to store programs when such programs are selected for execution, and to store instructions 158 and data that are read during program execution. The memory 154 may be volatile or non-volatile and may include ROM, RAM, ternary content-addressable memory (TCAM), dynamic random-access memory (DRAM), and static random-access memory (SRAM). The memory 154 is operable (or configured) to store information used by the controller 150 and/or any other logic and/or instructions for performing the function described in this disclosure.

The I/O interface 156 is configured to communicate data and signals with other devices. For example, the I/O interface 156 may be configured to communicate electrical signals with components of the refrigeration system 100 including valves 114, 118, 120, 122, 124, 126, 132, 134, 136, 142; sensors 144, 146; and compressors 102, 138. The I/O interface 156 may be configured to communicate with other devices and systems. The I/O interface 156 may provide and/or receive, for example, compressor speed signals, compressor on/off signals, valve open/close signals, temperature signals, pressure signals, temperature setpoints, environmental conditions, and an operating mode status for the refrigeration system 100 and send electrical signals to the components of the refrigeration system 100. The I/O interface 156 may include ports or terminals for establishing signal communications between the controller 150 and other devices. The I/O interface 156 may be configured to enable wired and/or wireless communications.

Although this disclosure describes and depicts refrigeration system 100 including certain components, this disclosure recognizes that refrigeration system 100 may include any suitable components. As an example, refrigeration system 100 may include one or more additional sensors configured to detect temperature and/or pressure information.

In an example operation of the refrigeration system 100, the refrigeration system 100 is initially operating with both evaporators 116, 128 in the refrigeration mode, as illustrated in FIG. 1. In this mode, valve 118 is open, first valve 126 and

second valve 132 of LT evaporator 128 are open, and third valve 136 and fourth valve 134 of LT evaporator 128 are closed.

At some point during operation of the refrigeration system 100, the controller 150 determines that defrost mode operation is needed for the LT evaporator 128. For example, the LT evaporator 128 may be scheduled for defrost at the time that has just been reached. After determining that the defrost mode operation is indicated, the controller 150 causes the LT evaporator 128 to be configured according to FIG. 2. In other words, the controller 150 causes the valve 134 to at least partially open to allow a portion of refrigerant from the auxiliary flash tank 130 to flow towards the heat exchanger 106. Valve 118 may be adjusted (e.g., partially closed) to increase the pressure of the auxiliary flash tank 130 relative to the pressure of the primary flash tank 112 to help drive the flow of refrigerant toward the heat exchanger 106. First valve 126 and second valve 132 are closed, and third valve 136 is opened.

Once defrost of the LT evaporator 128 is complete (e.g., because defrost mode operation has been performed for a predefined period of time and/or a threshold pressure and/or temperature 160 of the LT evaporator 128 has been reached), the controller 150 causes the LT evaporator 128 to operate in the refrigeration mode, as illustrated in FIG. 1 and described above.

Example Method of Operation

FIG. 3 illustrates an example method 300 of operating the refrigeration system 100 described above with respect to FIGS. 1 and 2. The method 300 may be implemented using the processor 152, memory 154, and I/O interface 156 of the controller 150 of FIGS. 1 and 2. The method 300 may begin at operation 302 where the controller 150 initially operates the evaporators 116, 128 in the refrigeration mode. At operation 304, the controller 150 determines whether defrost mode is indicated for any of the evaporators 116, 128. For example, the controller 150 may determine whether the instructions 158 and/or schedule 162 indicate that a defrost cycle is needed for one of the evaporators 116, 128. As another example, the controller 150 may determine whether a temperature and/or pressure 160 measured at an evaporator 116, 128 indicates decreased performance (e.g., if a target or threshold value 164 of temperature and/or pressure 160 is not being reached). This behavior may indicate that a defrost mode operation is indicated. If defrost mode is not indicated, the controller 150 returns to operation 302 and continues to operate the evaporators 116, 128 in the refrigeration mode. If defrost mode operation is indicated, the controller 150 proceeds to operation 306.

At operation 306, the controller 150 causes the evaporators 116, 128 determined at operation 304 to be operated in the defrost mode. For instance, if defrost of the LT evaporator 128 is needed, the controller 150 opens third valve 136 and fourth valve 134, closes first valve 126 and second valve 132, and adjusts valve 118 to increase the pressure of the auxiliary flash tank 130 relative to the pressure of the primary flash tank 112. This achieves the defrost mode configuration of evaporator 128 illustrated in FIG. 2.

At operation 308, the controller 150 determines whether defrost mode operation of the evaporator 128 is complete. For example, the controller 150 may determine whether defrost mode operation has been performed for a predefined period of time indicated by schedule 162 and/or if a threshold value 164 is reached for a pressure and/or temperature 160 of the LT evaporator 128. If defrost mode operation is not complete, the controller continues to operate in the defrost mode at operation 306. Once defrost mode operation

is complete, the controller 150 returns to operation 302 and operates the evaporator 128 in the refrigeration mode.

Modifications, additions, or omissions may be made to method 300 depicted in FIG. 3. Method 300 may include 5 more, fewer, or other operations. For example, operations may be performed in parallel or in any suitable order. While at times discussed as controller 150, refrigeration system 100, or components thereof performing the operations, any suitable refrigeration system or components of the refrigeration system may perform one or more operations of the method 300.

While several embodiments have been provided in the present disclosure, it should be understood that the disclosed systems and methods might be embodied in many other specific forms without departing from the spirit or scope of the present disclosure. The present examples are to be considered as illustrative and not restrictive, and the intention is not to be limited to the details given herein. For example, the various elements or components may be combined or integrated in another system or certain features may be omitted, or not implemented.

In addition, techniques, systems, subsystems, and methods described and illustrated in the various embodiments as discrete or separate may be combined or integrated with other systems, modules, techniques, or methods without departing from the scope of the present disclosure. Other items shown or discussed as coupled or directly coupled or communicating with each other may be indirectly coupled or communicating through some interface, device, or intermediate component whether electrically, mechanically, or otherwise. Other examples of changes, substitutions, and alterations are ascertainable by one skilled in the art and could be made without departing from the spirit and scope disclosed herein.

To aid the Patent Office, and any readers of any patent issued on this application in interpreting the claims appended hereto, applicants note that they do not intend any of the appended claims to invoke 35 U.S.C. § 112(f) as it exists on the date of filing hereof unless the words "means for" or "step for" are explicitly used in the particular claim.

What is claimed is:

1. A refrigeration system, comprising:
a plurality of evaporators, each configured to transfer heat from a space to refrigerant, wherein each of the plurality of evaporators has a sensor associated with it for measuring at least one of a temperature or a pressure; one or more medium temperature compressors configured to output compressed refrigerant; a first flash tank configured to receive and store cooled refrigerant provided by a gas cooler; a second flash tank configured to receive and store a portion of the cooled refrigerant from the first flash tank; an adjustable pressure-regulating valve disposed in refrigerant conduit coupling the first flash tank to the second flash tank, wherein when each of the plurality of evaporators is operated in a refrigeration mode the adjustable pressure-regulating valve is fully open and the first flash tank and second flash tank are held at a same flash tank pressure, wherein when at least one of the plurality of evaporators is operated in a defrost mode the adjustable pressure-regulating valve is at least partially closed and configured to selectively increase a first flash tank pressure in the first flash tank relative to a second flash tank pressure in the second flash tank; a heat exchanger positioned between an outlet of the one or more medium temperature compressors and an inlet

11

of the gas cooler, the heat exchanger configured to receive the compressed refrigerant from the one or more medium temperature compressors and provide the compressed refrigerant to the gas cooler, and when at least one evaporator of the plurality of evaporators is operated in the defrost mode, to transfer heat from the compressed refrigerant output by the one or more medium temperature compressors to a flow of refrigerant from the first flash tank; and a controller communicatively coupled to the pressure-regulating valve, wherein the controller is configured to:

determine that operation of a first evaporator of the plurality of evaporators in the defrost mode is indicated by the sensor associated with it, wherein the defrost mode is indicated when the measurement associated with the first evaporator is less than a threshold value; and

after determining that operation of the first evaporator in the defrost mode is indicated, cause the first evaporator to operate in the defrost mode by:

adjusting the pressure-regulating valve to increase the first flash tank pressure of the first flash tank relative to the second flash tank pressure of the second flash tank, wherein the controller is further configured to cause the first evaporator to operate in the defrost mode by partially closing the pressure-regulating valve;

allowing flow of refrigerant from the first flash tank to the heat exchanger based on the increased first flash tank pressure; and

allowing refrigerant heated by the heat exchanger to flow to the first evaporator.

2. The refrigeration system of claim 1, further comprising: a first valve located upstream from the first evaporator in refrigerant conduit coupling a liquid outlet of the second flash tank to the first evaporator, wherein, when the first evaporator is operating in the refrigeration mode, the first valve is open; and

a second valve located downstream from the first evaporator in refrigerant conduit allowing flow of refrigerant towards the one or more medium temperature compressors, wherein, when the first evaporator is operating in the refrigeration mode, the second valve is open; wherein the controller is further configured to cause the first evaporator to operate in the defrost mode by causing the first valve to close and causing the second valve to close.

3. The refrigeration system of claim 2, further comprising: a third valve located upstream from the first evaporator in refrigerant conduit coupling an inlet of the second flash tank to the first evaporator, wherein, when the first evaporator is operating in the refrigeration mode, the third valve is closed; and

a fourth valve located downstream from the first evaporator in refrigerant conduit coupling the first evaporator to the heat exchanger, wherein, when the first evaporator is operating in the refrigeration mode, the fourth valve is closed;

wherein the controller is further configured to cause the first evaporator to operate in the defrost mode by causing the third valve to open and causing the fourth valve to open.

4. The refrigeration system of claim 1, wherein the controller is further configured to:

determine that defrost mode operation of the first evaporator is complete; and

12

after determining that defrost mode operation of the first evaporator is complete, cause the first evaporator to operate in the refrigeration mode.

5. The refrigeration system of claim 1, wherein the flow of refrigerant from the first flash tank to the heat exchanger comprises vapor-phase refrigerant from the first flash tank or vapor-phase and liquid-phase refrigerant from the first flash tank.

6. The refrigeration system of claim 1, further comprising a flash gas bypass valve configured to allow at least a portion of vapor-phase refrigerant from the second flash tank to bypass the plurality of evaporators and be directed to the one or more medium temperature compressors.

7. The refrigeration system of claim 1, wherein, while the first evaporator is caused to operate in the defrost mode, a second evaporator of the plurality of evaporators is caused to operate in a refrigeration mode.

8. A method of operating a refrigeration system, the method comprising:

operating a first evaporator of a plurality of evaporators in a refrigeration mode, wherein each of the plurality of evaporators has a sensor associated with it for measuring at least one of a temperature or a pressure;

determining that operation of the first evaporator in a defrost mode is indicated; and

after determining that operation of the first evaporator in the defrost mode is indicated, causing the first evaporator to operate in the defrost mode by:

adjusting an adjustable pressure-regulating valve disposed in refrigerant conduit coupling a first flash tank to a second flash tank, the adjustable pressure-regulating valve configured to selectively increase a first flash tank pressure of the first flash tank relative to a second flash tank pressure of the second flash tank, wherein the first flash tank is configured to receive and store refrigerant cooled by a gas cooler and the second flash tank is configured to receive and store a portion of the cooled refrigerant from the first flash tank;

causing the first evaporator to operate in the defrost mode by partially closing the pressure-regulating valve;

allowing a flow of refrigerant from the first flash tank to a heat exchanger based on the increased first flash tank pressure, the heat exchanger positioned between an outlet of one or more compressors of the refrigeration system and an inlet of the gas cooler, wherein the heat exchanger is configured to receive the refrigerant from the one or more compressors and provide the refrigerant to a gas cooler and when the defrost mode is indicated, to transfer heat from the refrigerant received from the one or more compressors to the flow of refrigerant from the first flash tank to the heat exchanger; and

allowing refrigerant heated by the heat exchanger to flow to the first evaporator,

wherein the defrost mode is indicated by the sensor associated with the first evaporator when the measurement associated with the first evaporator is less than a threshold value.

9. The method of claim 8, further comprising causing the first evaporator to operate in the defrost mode by:

a first valve located upstream from the first evaporator in refrigerant conduit coupling a liquid outlet of the second flash tank to the first evaporator, wherein, when the first evaporator is operating in a refrigeration mode, the first valve is open;

13

a second valve located downstream from the first evaporator in refrigerant conduit allowing flow of refrigerant towards the one or more compressors, wherein, when the first evaporator is operating in the refrigeration mode, the second valve is open; and
5 causing the first evaporator to operate in the defrost mode by causing the first valve to close and causing the second valve to close.

10. The method of claim 9, further comprising:
a third valve located upstream from the first evaporator in refrigerant conduit coupling an inlet of the second flash tank to the first evaporator, wherein, when the first evaporator is operating in a refrigeration mode, the third valve is closed;
15 a fourth valve located downstream from the first evaporator in refrigerant conduit coupling the first evaporator to the heat exchanger, wherein, when the first evaporator is operating in the refrigeration mode, the fourth valve is closed; and
20 wherein the method is further configured to cause the first evaporator to operate in the defrost mode by causing the third valve to open and causing the fourth valve to open.

11. The method of claim 8, further comprising:
determining that defrost mode operation of the first 25 evaporator is complete; and
after determining that defrost mode operation of the first evaporator is complete, causing the first evaporator to operate in the refrigeration mode.

12. The method of claim 8, wherein the flow of refrigerant from the first flash tank to the heat exchanger comprises vapor-phase refrigerant from the first flash tank or vapor-phase and liquid-phase refrigerant from the first flash tank.

13. The method of claim 8, further comprising allowing, 35 by a flash gas bypass valve of the refrigeration system, at least a portion of vapor-phase refrigerant from the second flash tank to bypass the plurality of evaporators and be directed to the one or more compressors.

14. The method of claim 8, wherein, while the first evaporator is caused to operate in the defrost mode, a second 40 evaporator of the plurality of evaporators is caused to operate in a refrigeration mode.

15. A controller of a refrigeration system, the controller comprising:

an input/output interface communicatively coupled to an 45 adjustable pressure-regulating valve disposed in refrigerant conduit coupling a first flash tank to a second flash tank and configured to selectively increase a first flash tank pressure of the first flash tank relative to a second flash tank pressure of the second flash tank, wherein the first flash tank is configured to receive and store refrigerant cooled by a gas cooler and the second flash tank is configured to receive and store a portion of the cooled refrigerant from the first flash tank; and
50

a processor configured to:
55 determine that operation of a first evaporator of a plurality of evaporators in a defrost mode is indicated, wherein each of the plurality of evaporators has a sensor associated with it for measuring at least one of a temperature or a pressure and wherein the defrost mode is indicated by the sensor associated

5

14

with the first evaporator when the measurement associated with the first evaporator is less than a threshold value; and
after determining that operation of the first evaporator in the defrost mode is indicated, cause the first evaporator to operate in the defrost mode by:
adjusting the pressure-regulating valve to increase the first flash tank pressure of the first flash tank relative to the second flash tank pressure of the second flash tank;
allowing a flow of refrigerant from the first flash tank to a heat exchanger based on the increased first flash tank pressure, wherein the heat exchanger is positioned between an outlet of one or more medium temperature compressors and an inlet of the gas cooler, the heat exchanger configured to receive compressed refrigerant from the one or more medium temperature compressors and the heat exchanger provides the compressed refrigerant to the gas cooler; and
allowing refrigerant from the first flash tank to be heated by the heat exchanger to flow to the first evaporator,
wherein the processor is further configured to cause the first evaporator to operate in the defrost mode by partially closing the pressure-regulating valve.

16. The controller of claim 15, wherein:

the input/output interface communicatively coupled to:
a first valve located upstream from the first evaporator in refrigerant conduit coupling a liquid outlet of the second flash tank to the first evaporator, wherein, when the first evaporator is operating in a refrigeration mode, the first valve is open; and
a second valve located downstream from the first evaporator in refrigerant conduit allowing flow of refrigerant towards the one or more medium temperature compressors, wherein, when the first evaporator is operating in the refrigeration mode, the second valve is open; and
the processor is further configured to cause the first evaporator to operate in the defrost mode by causing the first valve to close and causing the second valve to close.

17. The controller of claim 16, wherein:

the input/output interface is further communicatively coupled to:
a third valve located upstream from the first evaporator in refrigerant conduit coupling an inlet of the second flash tank to the first evaporator, wherein, when the first evaporator is operating in a refrigeration mode, the third valve is closed; and
a fourth valve located downstream from the first evaporator in refrigerant conduit coupling the first evaporator to the heat exchanger, wherein, when the first evaporator is operating in the refrigeration mode, the fourth valve is closed;
wherein the processor is further configured to cause the first evaporator to operate in the defrost mode by causing the third valve to open and causing the fourth valve to open.
